M. M. McCashman

United States Patent Office.

M. M. CASHMAN, OF BOSTON, MASSACHUSETTS.

Letters Patent No. 70,801, dated November 12, 1867.

IMPROVEMENT IN CREEPING-ROBES FOR INFANTS.

The Schedule referred to in these Letters Patent and making part of the same.

TO ALL WHOM IT MAY CONCERN:

Be it known that I, M. M. CASHMAN, of Boston, in the county of Suffolk, and State of Massachusetts, have invented certain new and useful Improvements in Children's Creeping-Robes; and I do hereby declare that the following is a full and exact description thereof, reference being had to the accompanying drawings, and to the letters of reference marked thereon.

The nature of my invention consists in forming an annular bag or sack, the outer part of which serves as a loose dress or wrapper, covering the ordinary dress, while the inner part serves as a skirt inside of the ordinary dress of a child. The object of this garment, which I call a child's creeping-robe, is to protect the nicer garments of a creeping child from being soiled.

To enable others skilled in the art to make and use my invention, I will proceed to describe its construction and use. In the drawings—

Figure 1 is a view showing the creeping-robe as it appears upon the child.

Figure 2 is a section showing the dress and skirts of the child in the creeping-robe.

Figure 3 is a section of the creeper only.

I construct my improved creeping-robe as follows: An inner skirt, A Aⁱ Aⁱⁱ, figs. 2 and 3, is made of any suitable material, in the ordinary manner, being attached to the waist of the child by the band B, and is next to the drawers, being within the dress-skirts. Now I make a loose wrapper, A^{iv} Aⁱⁱⁱ Aⁱⁱ, which is large enough to enclose the entire dress of the child. This wrapper is connected at the lower edge, that is, at Aⁱⁱ, to the inner skirt, fig. 3, so that these two, that is, the inner skirt A Aⁱ Aⁱⁱ and the wrapper A^{iv} Aⁱⁱⁱ Aⁱⁱ form an annular sack or bag, enclosing the nicer garments D D, as shown in fig. 2. It will be readily understood by ladies that my improved creeping-robe may be put on after the child has been dressed, and be taken off without interfering with the customary dress of the child.

The advantage of my creeper is this: A child may be nicely dressed in the ordinary garments, and, being protected by my creeper, may be allowed to play upon the floor, as the creeper will protect the nice dress from being soiled. When desirable to have the child appear in clean garments, the creeper can be removed, thus saving the time and trouble of dressing the child again.

Having thus described my invention, I will proceed to set forth my claim. What I claim as my invention, and desire to secure by Letters Patent, is—

Forming a creeper, by uniting a skirt, A Aⁱ Aⁱⁱ, with a wrapper, A^{iv} Aⁱⁱⁱ Aⁱⁱ, substantially as shown and for the purpose set forth.

M. M. CASHMAN.
